UNITED STATES PATENT OFFICE.

BENJAMIN H. KELLOGG, OF SHERMAN, CONNECTICUT.

DEVICE FOR ATTACHING WHIFFLETREES TO CROSS-BARS.

SPECIFICATION forming part of Letters Patent No. 767,820, dated August 16, 1904.

Application filed April 25, 1904. Serial No. 204,686. (No model.)

To all whom it may concern:

Be it known that I, BENJAMIN H. KELLOGG, a citizen of the United States, residing at Sherman, county of Fairfield, State of Connecticut, cut, have invented a new and useful Device for Attaching Whiffletrees to Cross-Bars, of which the following is a specification.

My invention has for its object to provide a simple and inexpensive device for attaching a whiffletree to a cross-bar or evener which shall be adapted to attach a whiffletree of any thickness to a cross-bar or evener of any thickness and which, while leaving the whiffletree free to oscillate in the horizontal plane, will hold it against any oscillation or swinging whatever in the vertical plane, it being of course understood that movement of the whiffletree in the vertical plane produces an undue strain on the whiffletree-bolt and is not infrequently the cause of breakage of whiffletree-bolts.

With these and other objects in view I have produced the novel device for attaching whiffletrees to cross-bars and eveners which I will now describe, referring to the accompanying drawings, forming a part of this specification, and using reference characters to indicate the several parts.

Figure 1 is a plan view of my novel device, illustrating its application in attaching a whiffletree to a cross-bar; Fig. 2, a similar view illustrating its application in attaching a whiffletree to an evener; Fig. 3, a front elevation, on an enlarged scale, showing the device in use in attaching a whiffletree to an evener, and Fig. 4 is a section on the line 4-4 in Fig. 3.

10 denotes shafts of ordinary construction for a single wagon; 11, a cross-bar therefor; 12, a pole for a double wagon; 13, an evener 40 therefor pivoted to the pole, as at 14, and 15 a whiffletree, which may be of any ordinary or preferred construction and is shown as provided with the usual strengthening-plates 16 at top and bottom.

45 My novel device comprises simply upper and lower plates (denoted, respectively, by 17 and 18) a guard-plate 19, a bolt 20, and an ordinary whiffletree-bolt 21. It is an essential feature of the invention that the three

plates are made independent of each other, so as to adapt the device for use with any thickness of cross-bar or evener or of whiffletree. Plates 17 and 18 lie above and below the cross-bar or evener, the upper plate being preferably extended forward, as at 22, in order to give increased strength and also to form a convenient rest for the whiffletree in assembling. Bolt 20 passes through the guard-plate, the cross-bar or evener, and through both upper and lower plates. Just forward of the head of the bolt the guard-plate is curved upward and then forward to partly inclose the whiffletree, as clearly shown in Fig. 4. These guard-plates are formed for the market of average height and may be made of different sizes or may be slightly shaped at the time of use to adapt them for slightly thicker or thinner whiffletrees. The whiffletree, as already stated, rests upon the upper plate 17, and the forward end of the guard-plate lies just above the whiffletree, inclosing the top and back of the whiffletree, the whiffletree being given just sufficient room to permit it to oscillate freely. The whiffletree-bolt passes through the guard-plate, the whiffletree, the upper and lower plates, and down in front of the cross-bar or evener, as clearly shown in Fig. 4, so that the cross-bar or evener is not weakened by a hole for the whiffletree-bolt, the strain upon the evener being taken up by bolt 20, which passes through the cross-bar or evener near the back thereof.

Having thus described my invention, I claim—

1. A device for attaching whiffletrees to cross-bars or eveners, comprising plates adapted to lie above and below the cross-bar or evener, a guard-plate above the evener shaped to partly inclose the whiffletree, a bolt adapted to pass through the guard-plate, the upper and lower plates and the cross-bar or evener and a whiffletree-bolt adapted to pass through the guard-plate above the whiffletree, through the whiffletree and the upper and lower plates and in front of the cross-bar or evener.

2. A device for attaching a whiffletree to a cross-bar or evener comprising upper and

lower plates adapted to lie on opposite sides of the cross-bar or evener, a guard-plate above the upper plate and curved upward and forward to partly inclose the whiffletree, a bolt 5 adapted to pass through the guard-plate back of the whiffletree and through the upper and lower plates and the cross-bar or evener, and a whiffletree-bolt adapted to pass through the guard-plate above the whiffletree and through

the whiffletree and the upper and lower plates to and in front of the cross-bar or evener.

In testimony whereof I affix my signature in presence of two witnesses.

BENJAMIN H. KELLOGG.
